UNITED STATES PATENT OFFICE.

JAMES R. NEILSON, OF UNION CITY, TENNESSEE.

COMBINED RATCHET WRENCH AND DRILL.

No. 822,687.

Specification of Letters Patent.

Patented June 5, 1906.

Application filed July 12, 1904; Serial No. 216,221.

To all whom it may concern:

Be it known that I, JAMES R. NEILSON, a citizen of the United States, and a resident of Union City, in the county of Obion and 5 State of Tennessee, have invented a new and Improved Combined Ratchet Wrench and Drill, of which the following is a full, clear, and exact description.

This invention relates to a combined ratchet wrench and drill; and the principal object of the invention is to provide a device of the character specified which is simple and comparatively inexpensive in construction, which affords a very positive grip upon 15 the tool or other member gripped thereby, and which is provided with a reversible ratchet operating mechanism by means of which the combined wrench and drill may be positively rotated in either direction 20 about its axis of rotation.

With the object above stated and others of minor character in view, as will hereinafter appear, the invention consists in the novel combination and arrangement of parts, as 25 will be hereinafter pointed out, and the novel features of which will be specifically set forth in the claims.

A practical embodiment of the invention is hereinafter described in detail, and illustrated in the accompanying drawings, forming 30 a part of this specification, in which corresponding parts are designated by similar characters of reference throughout the several views.

Figure 1 is a view in side elevation of the complete apparatus forming the invention. Fig. 2 is a longitudinal vertical section through the structure shown in Fig. 1. Fig. 3 is an elevational view of the jaw-carrier and 35 one of the gripping-jaws mounted therein, part of the carrier being broken away to show the means for limiting the outward movement of the jaw. Fig. 4 is a sectional view on the line 4-4 of Fig. 3. Fig. 5 is an elevational view of the jaw-actuator and the upper end of the feed-screw mounted therein. Fig. 6 is a bottom plan view of the jaw-actuator. Fig. 7 is a side view of one form of 40 gripping-jaw, and Fig. 8 is a top plan view of 45 the jaw shown in Fig. 7.

The combined ratchet wrench and drill forming the present invention comprises a jaw-carrier channeled for a pair of oppositely-arranged sliding jaws, a jaw-actuator 50 rotatable within the carrier and adapted for producing movement of the jaws both into

and out of operative position, and a handle-lever mounted upon the jaw-carrier so as to be rotatable in relation thereto and provided with a spring-pressed pawl of special structure adapted for engagement with a plurality of recesses formed on the exterior of the jaw-carrier and serving, in connection with the spring-pressed pawl provided in the handle-lever, to form a ratchet mechanism for operating the wrench or drill. The jaw-actuator is provided with a feed-screw axially mounted therein and adapted to serve, when the device is used as a drill, to feed the drill positively into the material to be bored. 60 65 70

Referring to the drawings in detail, 1 designates the jaw-carrier, which, as best seen in Fig. 3, is of generally cylindric form and is provided at the bottom with an enlargement 2, which is transversely channeled with an undercut groove or way 3 for a pair of gripping-jaws 4 or 4^a, the jaws 4^a being adapted for gripping larger objects than the jaws 4, as will be readily understood. Above the enlargement 2 the jaw-carrier 1 is provided 75 upon its exterior with a plurality of recesses 5, each of which has substantially parallel sides and a concaved bottom, as clearly shown in Fig. 3. Above the recesses 5 the jaw-carrier is provided with a circumferential groove 6 very near the top to receive a screw by means of which the jaw-carrier and jaw-actuator are held in proper relation. The jaw-carrier is axially bored throughout 80 a portion of its depth, as clearly shown in Fig. 2, the bore forming a chamber 7. In the chamber 7 the jaw-actuator 8, which is of substantially cylindrical form, is rotatably mounted. The jaw-actuator has an enlargement 9 at its upper end, and in the under 85 surface of the shoulder formed by the enlargement there is an annular groove 10, into which the upper portion of the jaw-carrier fits. In the enlargement 9 of the jaw-actuator a screw 11 is secured in such position 90 that the end thereof will engage the base of the annular groove 6, that is formed on the exterior of the jaw-carrier, and will serve to hold the jaw-carrier and jaw-actuator in proper relation. At its lower end the jaw-actuator is provided with a spiral thread 12, 95 cut in the base of the actuator, as best shown in Fig. 6.

Each of the gripping-jaws 4 and 4^a is provided upon its upper surface with a plurality 100 of concentric segmental ribs 13, which are adapted for engagement with the thread 12,

formed on the base of the jaw-actuator, the ribs 13 being preferably formed with pointed ends, as shown in Fig. 8, to facilitate the passage of the thread between the ribs. The 5 said gripping-jaws are slideable in the way 3, formed to receive them in the enlargement at the lower end of the jaw-carrier, and they are held against complete disengagement from the jaw-carrier by one or more screws 14, mounted in the jaw-carrier and each of which engages with the base of a recess or slot 15 in one of the lateral faces of one of the clamping or gripping jaws. The recess 15, provided within each gripping-jaw, is 10 open at its outer end, but closed at its inner end, and consequently the outward movement of each jaw in the way provided for it in the jaw-carrier is limited by the contact of the end of the screw 14 with the closed inner 15 end of the recess 15, formed in the jaw. When the jaw-carrier and jaw-actuator are assembled, an annular depression is presented between the enlargement 2 of the jaw-carrier and the enlargement 9 of the jaw-actuator, and in this annular depression there is secured a band or collar 16, having at one side a lateral socket 17, which is preferably formed integral therewith and which is adapted to receive a hollow handle 18, 20 which is externally threaded for engagement with the socket 17, in which an internal thread is formed, as shown in Fig. 2. The hollow handle 18 is designed to receive a rod or stem 19, bearing at its inner end an enlargement 20, presenting one beveled face 21, the other face of the enlargement 20 being flat. The stem 19 is slideable within the hollow handle 18, and the enlargement 20 projects through an opening formed at the 25 inner end of the socket 17, so that the end of the said enlargement may engage with the sides of the recesses 5, formed on the outer surface of the jaw-carrier. The stem 19, with its enlargement 20, forms a pawl which 30 is held normally in operative engagement within one of the recesses in the jaw-carrier by means of a coil-spring 22, disposed within the hollow of the handle 18 and abutting at its outer end against a plug 23, fitted in the 35 outer end of the handle. At its inner end the spring 22 abuts against a pin 24, disposed transversely through the stem 19, as shown in Fig. 2, and consequently the rod 19 is pressed toward the inner end of the handle 18 by the spring. In order to prevent 40 rotation of the rod 19 within the handle 18 except when such rotation is desirable, the said rod is provided at its outer end with a square portion 25, which is disposed within 45 a squared opening in the plug 23. Upon the end of the rod 19 a head or cap 26 is mounted, which is preferably milled at its periphery, as shown, and this head or cap serves as a handle whereby the rod may be drawn outward 50 against the pressure exerted by the

spring 22 until the squared portion 25 of the said rod is no longer disposed within the square hole in the plug 23. The rod may then be turned by means of the head 26 until the inclined face 21 of the enlargement 20 at 55 the inner end of the rod is turned in a direction directly opposite to that in which it was formerly disposed. In this way the spring-pawl formed by the rod 19 and its enlargement is adapted to operate in either direction 70 and to provide for the opposite rotation of the jaw-carrier to the right or left, as may be desired.

To enable the device to be used as a drill, the jaw-actuator 8 is axially bored and internally threaded to receive a feed-screw 27, the head 28 of which is polygonal in cross-section and at the top is of conical form, tapering to a tolerably sharp point 29. The head 28 of the screw is also transversely pierced by an 80 aperture 30, designed to receive a lever by which the screw may be turned within the jaw-carrier to effect the feed of the drill at any desired rate.

When the device is in use as a wrench, the 85 jaws having been spread apart by the rotation of the jaw-actuator in the proper direction, the tool to be gripped by the wrench is interposed between the jaws, and the jaw-actuator is then rotated in the reverse direction until the jaws are brought into clamping engagement with the tool. The tool, of whatever character, is then applied to the purpose for which it is intended, or, if desired, the wrench may be applied to a nut or 90 bolt in precisely the same way, and the rotation of the nut or bolt in either direction may be brought about by the action of the spring-pawl coöperating with the sides of the recesses in the jaw-carrier to form a ratchet 105 mechanism.

When the device is to be used as a drill, the actuator having been locked to the carrier by tightening the screw 11, the boring-tool is clamped between the jaws, and the pointed end 29 of the head 28 of the screw 27 is brought into engagement with a suitable centering member, preferably provided with a conical depression for engagement with said point, and the boring-tool is placed upon the 110 material to be bored. The operation of the handle-lever with the ratchet set properly will rotate the drill, and by means of a rod or the like introduced into the opening 30 in the feed-screw the feed-screw may be given a 115 partial turn from time to time to effect the feed of the boring-tool into the material to be bored at any rate that may be desirable.

The gripping-jaws may be made of any necessary configuration for engagement with 120 the shank of the boring or other tools or with nuts of various sizes. It will, moreover, be desirable to provide with each wrench two or more sets of gripping-jaws, such as the jaws 4 and the jaws 4^a, in order to adapt the 130

wrench for use upon objects of various sizes. In fact the number of types of gripping-jaws which may be used is unlimited; but for ordinary purposes the two types of gripping-jaws shown will be sufficient. In applying the wrench to any object to be gripped thereby the rotation of the jaw-actuator is controlled by the hand of the user gripping the outer surface of the enlargement 9 of the said jaw-actuator, and this enlargement is preferably milled for the purpose, as shown in Fig. 1.

A special feature of advantage in the combined wrench and drill forming the present invention is the extremely positive grip obtained thereby and the fact that the action of the wrench does not produce strain upon the jaw-actuator of such character that the loosening of the grip is at all apt to occur. The direction of the strain upon the jaws is substantially perpendicular to tangents to the ribs provided on the jaws for engagement with the thread 12 on the jaw-actuator, and consequently the strain does not tend to produce any relative movement of the jaws and the actuator.

While I have described my invention in a preferred form of embodiment, it is to be understood that changes in the form, proportions, and mode of assemblage of the parts described and exhibited may be varied without departing from the spirit of the invention; and I do not, therefore, limit myself to the exact structure shown and described, but reserve the right to make changes therein within the scope of the appended claims.

Having thus described my invention, I claim as new and desire to secure by Letters Patent—

1. In a combined ratchet wrench and drill, a hollow jaw-carrier having an annular groove at its upper end and provided at its lower end with an enlargement having a transverse

channel therein, said carrier being formed with annularly-disposed recesses in the outer face of its body, a jaw-actuator within the carrier, said actuator having a spiral thread on its lower end and provided at its upper end with an enlargement having in its under face an annular groove receiving the upper end of the carrier, the enlargements of the carrier and actuator forming an annular depression, a screw in the enlargement of the actuator and engaging the groove of the carrier, a ring rotatable in said depression and having a handle, a spring-actuated pawl in the handle and having an end thereof normally received in one of said recesses, and movable jaws in the channel of the carrier and provided on their upper faces with segmental ribs engaging the thread of the actuator.

2. In a combined ratchet wrench and drill, a hollow jaw-carrier provided with an enlargement at its lower end and an annular groove at its other end, the enlargement having a transverse channel therein, movable jaws in the channel, a jaw-actuator within the carrier having at its upper end an enlargement formed in its under side with an annular groove, the upper end of said carrier being received by said groove, a binding-screw entering the side of the enlargement of the actuator and engaging the groove of the carrier, means for operating the jaws from the actuator, and means for rotating the carrier, including a rotatable ring between the enlargements of the carrier and the actuator and provided with a handle.

In testimony whereof I have signed my name to this specification in the presence of two subscribing witnesses.

JAMES R. NEILSON.
